Primary Examiner — Dana Meyrow(74) *Attorney, Agent, or Firm* — Wood Herron & Evans LLP(57) **CLAIM**

The ornamental design for a cup for a yogurt product therefor, as shown and described.

DESCRIPTION

FIG. 1 is a top, front, left side perspective view of a cup for a yogurt product according to the present invention;

FIG. 2 is a front elevation view thereof, the rear elevation view being identical;

FIG. 3 is a left side elevation view thereof, the right side elevation view being a mirror image;

FIG. 4 is a top plan view thereof;

FIG. 5 is a bottom plan view thereof; and,

FIG. 6 is a cross-section view taken along the line **6-6** in FIG. 3.

The unshaded areas in the drawings shown in broken lines illustrate the portions of the cup for a yogurt product that form no part of the claimed design. The inside of the cup for a yogurt product shown in FIG. 6 is not included in the claim thereof.
